UNITED STATES PATENT OFFICE.

MARION PATTERSON, OF STEWARDSON, ILLINOIS.

HARVESTER.

SPECIFICATION forming part of Letters Patent No. 772,820, dated October 18, 1904.

Application filed June 7, 1904. Serial No. 211,522. (No model.)

To all whom it may concern:

Be it known that I, MARION PATTERSON, a citizen of the United States, residing at Stewardson, in the county of Shelby and State of Illinois, have invented new and useful Improvements in Harvesters, of which the following is a specification.

My invention relates to new and useful improvements in harvesters; and its object is to provide a simple and compact machine of this character having a revoluble sickle which is adapted to be operated by the wheels upon which the machine is mounted.

A further object is to provide reels for directing stalks upon the sickles during the forward movement of the machine.

Another object is to provide means whereby the stalks can be bundled upon the machine.

The invention consists of the novel construction and combination of parts hereinafter more fully described and claimed, and illustrated in the accompanying drawings, showing the preferred form of my invention, and in which—

25 Figure 1 is a plan view of the complete machine. Fig. 2 is an enlarged top plan view of the machine, a portion of the platform being removed to show the clutch thereunder and the dumping device being removed. Fig. 3 is a 30 section on line 2 2, Fig. 1. Fig. 4 is a central longitudinal section through the machine, the dumping device being removed therefrom; and Fig. 5 is an inner elevation of one of the wheels.

35 Referring to the figures by numerals of reference, 1 is a platform which is supported upon an axle 2, having ratchets 3 thereon, which are adapted to be engaged by spring-pressed pawls 4, secured to the hubs of wheels 40 5. These pawls and ratchets are so arranged that when the machine is traveling forward the pawls engage the ratchets, but movement of the machine in the opposite direction causes the pawls to slip over the ratchets. A sprocket 45 6 is secured to axle 2 and rotates therewith, and this sprocket has a chain 7 mounted thereon, which transmits rotary motion to a small sprocket 8, loosely mounted on a shaft 9, which is journaled in hangers 10, located upon the

bottom of platform 1. Shaft 9 extends transversely of the machine, and adjacent each end thereof is located a beveled gear 11, which meshes with a similar gear 12, secured to the lower end of a vertical shaft 13, which is revolubly mounted within the platform 1, adjacent the side thereof. Secured to the upper end of each shaft 13 is a head 14, having sockets 15 therein, in which are detachably mounted arms 16, which constitute reels.

Extending forward from the center of platform 1 is a similar platform 17, having a caster 18 located under its forward end, and thills 19 or other like draft devices are connected to and are adapted to move the caster for the purpose of guiding the machine. Arranged on this platform is a seat 20 for the driver, and a lever 21 is fulcrumed adjacent this seat and operates a lever 22, which is fulcrumed under the platform 17 and is connected to a clutch 23, slidably mounted on shaft 9. This clutch is adapted to lock or unlock the sprocket 8 upon the shaft 9. Fingers 24 are arranged at the front of platform 1, at the sides thereof, and extend to opposite sides of platform 17, and the forward ends of these fingers are tapered, so as to guide stalks inward toward platform 17 and upon rotary disks 25. These disks are located between the fingers 24 and platform 17, and each disk has saw-teeth and is secured to a short shaft 75 26, on which is fastened a beveled gear 27. The beveled gears of the two disks mesh with similar gears 28, secured to shaft 9.

A partition 29, having converging walls, is arranged longitudinally upon the center of platform 1, and located along the sides of this platform are inclined flanges 30, the forward ends of which are enlarged and extend in rear of the shafts 13. Revolubly mounted under the rear portion of platform 1 are 90 shafts 31, which are converging and have fingers 32, the ends of which overlap to form a crib for the reception of stalks subsequent to their discharge upon the platform 1. Each shaft 31 has an arm 33, which is connected by 95 link 34 with a bell-crank lever mounted upon the bottom of platform, and the bell-crank levers of the two shafts 31 are connected by

rods 36 and with a treadle 37, located adjacent to the seat 20.

- When the machine is drawn forward, the wheels 5 will rotate axle 2 and rotary motion will be transmitted through chain 7 to shaft 9. The cutting-disk 25 will thus be turned in the direction indicated by the arrows in Fig. 2, and the reel-arm will also be rotated in the directions shown by arrows thereon.
- 10 As the machine moves forward the fingers 24 will guide the stalks inward toward the platform 17 and to the rotary cutters, while the arms 16 of the reels will after the stalks have been severed by the cutters deliver them onto the platform 1, where they will form in bundles between the inclined walls 29 and flanges 30 and will be finally delivered in any usual or appropriate manner to the crib-fingers 32, it being understood, of course, that these parts operate in the ordinary manner. After a sufficient quantity of stalks have accumulated upon these fingers the same can be dumped by pressing on the treadle 37. This in turn will cause the shaft 31 to rotate so as to swing the fingers 32 downward. The parts can then be returned to their normal positions and the operation repeated. When it is desired to prevent the disks and reels from operating during the movement of the machine,
- 25 30 it is merely necessary to disconnect clutch 23 from sprocket 8 by means of lever 21. The ratchets 3 and pawls 4 permit one or both of the wheels 5 to move backward without rotating the axle 2. The machine can be used for cutting any vegetable growths standing in rows, and either one or two rows can be simultaneously cut thereby.

In the foregoing description I have shown the preferred form of my invention; but I do not limit myself thereto, as I am aware that modifications may be made therein without departing from the spirit or sacrificing any of the advantages thereof, and I therefore re-

serve the right to make such changes as fairly fall within the scope of my invention. 45

Having thus described the invention, what is claimed as new is—

1. In a machine of the character described, the combination with a platform having centrally - arranged longitudinally - extending 50 guide-walls, and guide - flanges at the sides of the platform, of cutting-disks at one end of the platform and between the guide walls and flanges, fingers extending forward from the sides of the platform for directing material against the disks, reels above the disks for throwing severed material between the guide walls and flanges, means for transmitting rotary motion to the disks and reels during the forward movement of the platform, a crib formed of movable fingers at the rear end of the platform for receiving material propelled by the reels. 55

2. In a machine of the character described, the combination with a platform having a 60 centrally-arranged extension at one end, longitudinally-extending inclined guide - walls upon the platform and in rear of the extension, and guide - flanges at the sides of the platform; of a crib in rear of the platform 70 and comprising converging revoluble shafts and overlapping fingers extending therefrom, cutting-disks at the opposite end of the platform and at opposite sides of the extension, reels thereabove for throwing the severed material between the guide walls and flanges and upon the crib, forwardly-extending fingers at the sides of the platform, and mechanism operated from the extension for rotating the shafts. 75

In testimony whereof I affix my signature in presence of two witnesses.

MARION PATTERSON.
